(57) **CLAIM**

The ornamental design for a tool pouch with rotatable cover, as shown and described.

DESCRIPTION

FIG. 1 is a perspective view (as seen from the front view) of the tool pouch with rotatable cover in a closed position.

FIG. 2 is a front view (as seen from the side view with rotatable cover in a closed position) thereof.

FIG. 3 is a rear view thereof.

FIG. 4 is a right side view (with rotatable cover in a closed position) thereof.

FIG. 5 is a left side view (with rotatable cover in a closed position) thereof.

FIG. 6 is a top view (with rotatable cover in a closed position) thereof.

FIG. 7 is a bottom view (with rotatable cover in a closed position) thereof.

FIG. 8 is a perspective view (as seen from the rear view with rotatable cover in a closed position) thereof.

FIG. 9 is a perspective view (as seen from the front view) of the tool pouch with rotatable cover in an open position.

FIG. 10 is a front view (with rotatable cover in an open position) thereof.

FIG. 11 is a rear view thereof.

FIG. 12 is a right side view (with rotatable cover in an open position) thereof.

FIG. 13 is a left side view (with rotatable cover in an open position) thereof.

FIG. 14 is a top view (with rotatable cover in an open position) thereof.

FIG. 15 is a bottom view (with rotatable cover in an open position) thereof; and,

FIG. 16 is a perspective view (as seen from the rear view with rotatable cover in an open position) thereof.

The small broken or dashed lines are used in the drawings to show the environment related to the claimed design and form no part of the claimed design. The more bold larger dashed lines are used to show stitching which is part of the environment and form no part of the claimed features. The longer irregular dashed lines are used to show curvature.
